UNITED STATES PATENT OFFICE.

ETIENNE E. H. ROUSSEAU, OF PARIS, FRANCE.

APPARATUS FOR UTILIZING THE FORCE OF FLUIDS, AIR, AND WATER.

SPECIFICATION forming part of Letters Patent No. 276,079, dated April 17, 1883.

Application filed August 25, 1882. (No model.) Patented in France May 22, 1882, No. 149,047.

To all whom it may concern:

Be it known that I, ETIENNE EMILE HENRI ROUSSEAU, a citizen of the Republic of France, residing at Paris, France, have invented certain new and useful Improvements in Apparatus for Utilizing the Force of Fluids, Air, and Water, (which has been patented by me in France under patent dated May 22, 1882, No. 149,047;) and I do hereby declare the following to be a full, clear, and exact description of the same, such as will enable others skilled in the art to which it appertains to make and use the same, reference being had to the accompanying drawings, and to the letters or figures of reference marked thereon, which form a part of this specification.

The apparatus the subject of the present invention is intended to utilize the force of moving fluids, the air, the tides, and so forth, without any special construction or building wherein to work the machine, which is simple, inexpensive, easily manufactured, and requires little attention when in operation. It is intended to be employed in a similar manner to wind-mills, turbine, screw, or hydraulic wheels of any kind, sails of vessels, for working machinery on the spot or at a distance, in generating power for electric lighting, heating, and in metallurgical processes. In accordance with its varied and multiple applications, the apparatus is formed either of one, two, three, or more similar planes, each consisting of a rigid frame bearing juxtaposed a series of contiguous blades, and supported like a door on hinges or some equivalent, and turns on one of its four sides in a particular manner, which is previously determined by arranging the series of blades so that they are placed in front or rear of the axis which bears the next series of blades. The frame then presents either a plain and impenetrable surface or leaves a free passage to the fluid in which it moves, as may be required.

Figure 1 represents an apparatus of the description referred to, seen in elevation. Fig. 2 shows the frames of which the apparatus is formed, with rectangular movable blades, as well as their mode of suspension. Fig. 3 represents the method of connecting the planes formed by the frames to collars mounted on the vertical axis of the apparatus. Fig. 4 is a plan view, and Fig. 5 shows a forked piece re-

ceiving the stop-knot of the tension-cord (hereinafter mentioned) of the planes, all of which parts are more fully described in this specification.

The following is a description of the apparatus as employed for utilizing the power of the wind: A fixed vertical axis, E, capable of being strengthened by four arms passing above the rest of the machine, supports three vertical planes, F, which turn on the said axis, and are separated one from the other about one hundred and twenty degrees. Each of these similar planes consists of a frame—rectangular, for example—bearing at intervals of fifty centimeters a galvanized-iron cord stretched horizontally, and of a diameter in proportion to its length or the resistance it has to oppose. To each horizontal rope are suspended by two or more rings or clasps frames or rectangular blades G, measuring, say, one meter broad by fifty-two centimeters high. These blades are juxtaposed, and can turn on the upper cord which supports them in front to rear, but not rear to front, on account of the position of the cord or rope supporting the series of blades immediately below. The small frames are made of rings of osier wood, or by an iron rod bent at three points at right angles, so as to form a frame bearing a cloth or sail surface of some material or of bitumenized paper; or, better still, the surfaces of these small frames consist of a small thin blade of sheet-iron protected from oxidation and pierced with one or several holes for receiving the catches or rings g, by which they move round the upper iron cord.

The horizontal stretched iron wires may in distant lands be replaced by rods or wooden poles, and ligaments employed in lieu of hinges. Near the top of the column or mast, which serves as axis to the apparatus, is a collar, H, turning with little friction on the mast by running on rollers h, borne by a piece or block, I, fixed on the mast.

In very simple apparatus the collar turns supported by a pin or bolt traversing the mast. The collar has three half-rings, i, at equal distances one from the other. Each half-ring receives a ligament, fixing to the collar the upper and inner angle of one of the three planes. Toward the base of each plane is another collar, also provided with half-rings to serve a

like purpose to the first-named ones. A third collar may, if desired, be placed in the center half-way between the others. The two or three collars, if three are used, are connected one with the other by metal or wooden bars, which makes them solid. The vertical bars and collars together form a muffle, the end of which above the lower level of the vertical planes is continued, and bears a drum on which the endless band intended to transmit motion is placed. This endless band passes under the circular rail, which bears the three planes at their lower and external end by means of small rollers. The constant outspread of the three planes is assured as follows, at the same time that the facility of closing them in case of need is established: Of the three planes, A is connected to B at one point and to C at the other by ropes K, which unite the upper external angles of each plane, as well as the lower external angles. The maximum of spread or extension cannot therefore exceed one hundred and twenty degrees between A B and C D. Two ropes of the same length connect B C; but by pulling on a cord, l, these two cables can be raised at one end out of the fork M, (see Fig. 5,) which receives their knots or checks. In this case the planes B C turn on the axis and rest against the plane A. All three planes together then only present their edges to the wind, and the apparatus ceases to work. To more clearly explain this, suppose for a moment that the three planes are resting one against the other in front of the spectator, who is in a line with the direction of the wind. The blades whose combination each form one of the planes all rest to the left of the iron wire or cord supporting the series of blades immediately below. The result is, whatever the direction of the wind, the apparatus will always turn from left to right. In constructing the apparatus the blades may also be placed to the right of the lower iron cord. The rotary motion will then be inverted, and the apparatus will turn from right to left. Then, supposing the two great planes B C led to their respective positions—that is to say, stretched away from the plane A the third of the circumference—the apparatus will at once commence to work, and will so continue without a dead-point, and no matter what the direction of the wind and without any particular care or supervision.

The plane C allows the wind to lift all its blades, which, turning ninety degrees on the iron cord supporting them, take a horizontal position and leave a free passage to the ambient fluid. The plane A, presenting its edge to the wind by simple weight, has all its blades resting against the horizontal axes and offers no resistance. The plane B presents a perfectly impenetrable surface to the wind and its blades rest against the horizontal axes more firmly the more energetic or violent the wind is. This plane therefore easily gives to the winds pressure and reaches A'. (See Fig. 4.)

At this juncture the plane has its blades ver-

tical by the effect of the weight, and the plane A has replaced the plane C and lets the air pass freely. The plane C in its turn opposes an impenetrable surface to the wind, and the apparatus continues to turn with a force which can be utilized proportionate to that of the decimeter square surface of one of the frames multiplied by the weight of a cubic diameter of air, and by the speed of the wind at the time. Should the wind change, the apparatus will nevertheless continue to turn in the same direction, having once been fixed in the proper position. Supposing that each plane measures ten meters high by twenty meters broad, the surface will be two hundred square meters or twenty thousand decimeters square, that the wind blows at a speed of ten meters to the second, and weighs one gram twenty-nine centimeters to the liter, we shall have constantly each second on the left part of the axis of the apparatus a pressure equal to thirty horse-power, working day and night, indefinitely, consuming nothing and costing hardly anything to set up.

The great economical and social benefits of this apparatus are simply incalculable. In large towns and cities, as well as in villages, where the apparatus would be employed in the rivers and water-courses for working mills, &c., it would tend greatly to increase the prosperity of the population. The apparatus, as used for utilizing the force of the rivers, streams, or tides, is exactly similar to that used for the wind. In this case the vertical axis is solidly driven into the earth, and three planes formed of frames with movable blades are arranged as already described, their height being equal to that of the highest level of the water at its highest mark. The breadth of each plane is less than usual in the air. The recommendation is to make each plane in breadth two-thirds of the depth of the water. It is more difficult in the water than in the air to make the lower portion of the planes rest on circular rails, (and concentrically if there are many.) The weight of these is considerable, as they are made of cast-iron for the mast and sheet-iron for the blades.

On the right and left banks of the river or stream, up and down the center of the town through which a river flows, it is easy to erect one or more series of these apparatus. The drum on which the endless band turns for transmitting the force is above the muffle instead of below it, as in the case for utilizing the force of the winds. It is best also to alternate the movements of each apparatus—that is to say, for one turning left to right, the two next turn from right to left above and below the first one, according to the flow of the water. The force of the fluid in motion will then be best utilized. It is advisable to bind the summits of all the masts together by light iron beams arranged at the left or right banks of the river or stream, which in no way hinders navigation. A galvanized-iron-wire grating is arranged around the parts of the water-

course where the apparatus are set up. By placing plates over the beams, which are recommended, an examination of the apparatus is easily effected should one or other of them require attention from some cause or other. The constant outspread of the three planes is maintained by thin rigid rods having a knee at half their length, and admits of stopping any of the apparatus, if desired. Should there be on a single bank three contiguous series of one hundred apparatus, with five meters depth of water, supposing the breadth of each plane equal to the depth of the water in a length of one kilometer of water-course, a speed of flow of one meter per second, or thirty-one to thirty-two meters broad, there will be night and day one hundred horse-power working without noise, and gratuitously, instead of requiring steam-machinery or gas, using five hundred to six hundred grains of coal per hour per horse-power, and stokers and engine drivers, whose wages are great, are avoided. This enormous force can be applied to machinery raising water or for compressing air with Gramme machines, Siemens, or others for transmitting motion or conveying power at a distance to accumulators, such as Planté's, Camille's, or Faure's.

It should be observed that, if there is nothing to interfere with it, an apparatus such as described, of relatively small proportions, may be established above a house for ventilation by supplying in hot weather quantities of com-

pressed air, which, when expanded, absorbs the heat and refreshes the confined atmosphere by renewing it; also for the production of electric currents for alarms, the automatic opening and closing of doors. The frames, being united three and three on an axis, as in the two preceding descriptions, or two and two, are always made as described—that is, rigid, with blades which can oscillate or be raised, so that the frame moves from front to rear, bottom to top, so that the fluid to which the surface is exposed finds a free passage, and also from rear to front, top and bottom. The circumscribed surface, either plain or curvilinear, is impenetrable and opposes an absolute resistance, which is the general principle of the invention.

What I claim is—

1. The herein-described wind and water wheel, consisting of a set of vertical frames which revolve around a common axis and are provided with hinged overlapping blades, substantially as described.
2. The wind and water wheel consisting of a set of vertical frames connected by ropes K, and arranged to revolve about a common vertical axis, each of said frames being faced with overlapping hinged blades, substantially as described.
